UNITED STATES PATENT OFFICE.

CHARLES SCHLAYER, OF NEW YORK, N. Y., ASSIGNOR OF ONE-HALF TO CHARLES W. JACOB, OF NEW YORK, N. Y.

CARBURETER ATTACHMENT.

1,007,010.

Specification of Letters Patent. Patented Oct. 24, 1911.

Application filed May 3, 1910. Serial No. 559,064.

To all whom it may concern:

Be it known that I, CHARLES SCHLAYER, a citizen of the United States, residing in the borough of Manhattan, in the city, county, and State of New York, have invented certain new and useful Improvements in Carbureter Attachments, of which the following is a specification, reference being had therein to the accompanying drawings, 10 which form a part thereof.

My invention relates to carbureter attachments and more particularly to a mixer thoroughly commingling the fuel vapor and air entrained therewith.

15 There have been heretofore devised various devices embodying a rotary propeller member adapted to be actuated by the suction created by the piston stroke through the moving column of mixed gases, but in 20 practice this type of mixer possesses the serious defect of an obstructing agent of constant and large area arranged in the duct to the engine and a centrifugal action tending to eliminate the vapor or other heavier 25 gas and concentrate it about the walls of the conduit. There is also a tendency for the carbureter fuel to congeal adjacent to the inlet port of the engine which has been a source of much engine trouble. A further 30 defect has been the necessity for a specially constructed conduit in order to adapt the device to existing structures of conduit and manifold.

The main object of my invention is to provide 35 a mixing attachment of this character which will by the thorough commingling of the vaporized fuel and air prevent the stratification of such and thus supply a practically dry mixture to the engine thus not only 40 effecting a saving by reason of the more thorough admixture of the vapor and air, but insuring increased capacity of the engine with a given quantity of fuel by reason of the greater uniformity of the mixture 45 supplied thereto upon successive cycles. Incidentally, the attainment of this object would have the effect of avoiding excessive fouling of the engine cylinders.

A further object is to provide a mixing 50 attachment for a carbureter which will present a substantially direct channel for the transmission of the charge, which channel will be of constant capacity and will have arranged therein a rotating member actuated by the flowing mixture, serving to

break up the column of gas, while not, at any point, materially interrupting the volume of the flow or developing such centrifugal force as to tend to separate the constituents of the mixture passing to the 60 engine.

A still further object is to provide a mixing attachment for carbureters which will avoid the stratification of vapor and air passing through the conduit to the manifold 65 without materially diverting or impeding the flow of gas.

A still further object is to provide a device of this character which may be housed in an ordinary conduit extending from the 70 carbureter to the manifold.

A still further object is to provide an attachment of this character wherein the gases flowing to the engine will be first thoroughly mixed to prevent stratification 75 and then screened or filtered to avoid the fouling of the engine valves by solid particles held in suspension by the flowing gases, the screen or filter serving the additional purpose of still further breaking up the 80 column of gas without substantially impeding the velocity thereof.

A still further object is to provide a simple attachment of this character which will be composed of two separate parts one 85 of which will include the rotary mixer and the other of which will include the screen or filter thus facilitating both the manufacture and installation of the device.

A still further object is to provide an agitator blade in an attachment of this character which will offer but little resistance to the flowing gases, while avoiding the presence of direct channels through which the gas may flow without being acted upon by 95 said agitator. And a still further object is to provide an attachment of this character, which will, while thoroughly commingling the vaporized fuel and the entrained air permit each stroke of the engine to draw in a 100 full charge of explosive mixture.

The invention consists in the novel features of construction and combination of parts as are hereinafter set forth and described, and more particularly pointed out 105 in the claims hereto appended.

Referring to the drawings:—Figure 1 is a side elevation of a mixing attachment for carbureters embodying my invention; Fig. 2 is a similar view with the lower portion of 110

the shield broken away to disclose the interior construction, and, Fig. 3 is a top view of the agitator section.

Like letters refer to like parts throughout the several views.

In the embodiment of my invention shown in the drawings, I have shown a bi-part structure consisting of two cylindrical portions *a* and *b* one of which as *a*, carries an agitator *c* and the other part *b* of which carries a filter or screen *d*. These parts are separately connected by means of a bayonet slot and pin connection, as shown in Fig. 1 of the drawings. The part *b* also has a plurality of projections *e* adapted to enter between the adjoining ends of pipe sections in the intake conduit (indicated in dotted lines in Fig. 1) for the purpose of preventing the creeping or displacement of the attachment in its entirety. The projections *e* therefore serve as a means for securing the attachment in the conduit, although, if desired, the cylindrical casing *a* or *b* might have a driving fit within the conduit.

The screen or filter *d* comprises a fine mesh, metallic screen projected in the direction of flow of the mixture, said screen being of gradually reduced diameter, being shaped somewhat like a truncated cone, the entire area of the openings of said screen permitting the egress of the mixture at all points in the direction of flow thereof, thus avoiding any substantial retardation of the flowing gases.

The casing *a* has at the opposite ends thereof and extending diametrically across same, parallel bars *f* *g* of small dimensions each of which bars has a screw-threaded opening *f* *g* carrying an exteriorly screw-threaded adjustable ball cup having a slotted head to facilitate the adjustment thereof. Mounted in said cups are single ball bearings *i*.

Mounted in the bearings afforded by the cups *h* *i* is a rotatable shaft *j* having rigidly and permanently attached thereto a helicoidal strand *k*, the greatest diameter of which is such as to bring it into close proximity to the casing *a*, and the pitch of which is such as to avoid the presence of a fixed channel through the agitator, the operative element of which is the strand *k*. Preferably this strand is composed of round copper wire to avoid any possible pocketing or obstruction of the gases; and to insure higher efficiency, a double oppositely pitched helicoidal agitator is used (as shown clearly in Fig. 2 of the drawings), thus not only minimizing any possibility of the presence of a direct channel through the agitator, but at the same time increasing longitudinally the effective range of operation thereof without presenting any substantial obstruction to the flow of the gases. This construction also insures the rotation of the

agitator by the flowing gases through the engagement of said gases with the forward helicoidal portion thereof, thus permitting the remainder of the agitator to act directly upon the column of gas.

It will be observed that by the construction above referred to, at no point within the casing *a*, is there any substantial obstruction to the flow of gases nor any such obstruction as would tend to deflect the gas toward the casing *a*, the impact of a column of gas passing through the casing *a* with the agitator *k* occurring at different points relative to the casing *a*. The rounded surface of the strand *k* offers barely enough resistance to the flowing gas to secure the desired rotary movement thereof, and the effect of said strand upon the gas is merely to divide same, the rotation of said agitator resulting from the action of the gas due to the suction from the engine causing the interruption or agitation of the entire column of gas in a manner to thoroughly mix the vapor and the air, rather than to separate the heavier vapor from the lighter air through centrifugal action.

I have found by actual use that with a mixer of the character described, I secure higher engine efficiency with a given quantity of fuel. This I attribute to the more thorough commingling of the vapor and the air, which results in a drier mixture, or rather a mixture carrying less vapor in suspension as such a mixture would be more highly explosive than would be the case otherwise. This condition results in greater economy in running an engine. I have also found that when using the mixer attachment, I experience no difficulty at the engine intake. This I attribute to the thorough admixture of the vapor and the air, without limiting or varying in any way the quantity of fuel introduced by each suction stroke of the engine by an obstruction in the intake pipe or in the manifold pipes. I have also found that the danger of back firing through the intake valve is practically eliminated when this device is used. These conditions result from the mode of operation peculiar to the structure herein described which is substantially as follows:— The sections *a* *b* having been by the pin and bayonet slot connection, the mixer in its entirety is inserted in the vapor feed pipe or the manifold leading therefrom to the different cylinders with the filter or screen *d* projecting toward the engine or in a direction coinciding with the flow of the gases therethrough, the open mouth of the casing *a* being exposed toward the carburetor proper. The parts being so arranged, with each suction stroke of the engine piston the carbureted vapor is drawn through the casings *a* *b*. Passing through the first of these casings, the mixture will rotate the heli-

coidal agitator *c*, the strand *k* thereof being pitched at every point thereof from the vertical, or relative to the radii of said casing and presenting no flat surfaces toward the carbureter, thus not retarding the flow of the mixture materially or diverting it from a substantially direct course through the casing *a*, while intercepting it at substantially every point of its course to an extent to cause a thorough admixture of the vapor and air. The centrifugal action of the agitator *c* is insufficient to eliminate any material quantity of the heavier matter in the mixture and the helicoidal arrangement of the strand *k* affords a continued beating action upon the column of gas sufficient to secure the thorough agitation thereof with the resultant formation of a substantially "dry" mixture prior to its introduction to the engine. As the entire volume of air enters the screen or filter *d* the contour of said parts permits the escape of gas in a volume practically coinciding with the area of the casing *b*, thus placing no limitation upon the volume of the mixture passing to the engine as compared with that leaving the carbureter. Furthermore, the construction and arrangement of this screen or filter permits the application of a strong suction through the carbureter itself which will of itself tend to increase the efficiency of the entire feed system including the mixer.

The arrangement of the agitator *c* and the screen *d* in sequence as shown and described, is desirable, as under most conditions of use the filter or screen is an essential adjunct and to place it between the agitator and the carbureter would not only tend to eliminate the vapor held in suspension in the air, but would lead to the rapid clogging of the screen or filter itself. If it be desired to use the agitator alone, the bi-part construction of the mixer permits the removing of the screen, and this construction also facilitates the cleaning of the said screen. It is to be observed that the arrangement of the agitator and of the screen or filter is such as to interpose no substantial obstruction in the course of the charge being drawn to the engine, thus preserving normal condition throughout the vapor feed system, while insuring a more thorough mixture than is secured when merely a vapor jet and entrained air are used.

It is well known that the efficiency of any gas distribution system is impaired by the presence of any obstructions which would tend to divert the direction of the flow of gas and I attribute the results attained by the actual use of my attachment to the absence of any such conditions, coupled with the absence of any direct channels which might lead to the stratification of the vapor or of the air while passing from the carbureter proper to the engine cylinder.

In the accompanying drawings I have shown my invention in that form which I have found to possess high efficiency in actual use, but nevertheless, I do not intend to limit myself to the precise details of construction embodied in the device shown in the drawings, it being apparent that such may be varied without departing from the spirit and scope of the invention.

Having described the invention, what I claim as new and desire to have protected by Letters Patent, is:—

1. In a carbureter attachment an agitator arranged in the pipe between the carbureter proper and the engine embodying therein a rotatable agitating member the effective area of which is spaced away from its axis of rotation and intersecting substantially the entire area of said pipe but upon different planes, both radially and axially thereof.

2. In a carbureter attachment an agitator arranged in the pipe between the carbureter proper and the engine embodying therein a rotatable agitating member the effective area of which is spaced away from its axis of rotation and intersecting substantially the entire area of said pipe but upon different planes, both radially and axially thereof, and a filter or screen arranged between said agitator member and the engine intake.

3. In a carbureter attachment an agitator arranged in the pipe between the carbureter proper and the engine embodying therein a rotatable agitating member the effective area of which is spaced away from its axis of rotation and intersecting substantially the entire area of said pipe but upon different planes, and a truncated conic filter or screen open at the base and extending from adjacent to said agitator with its reduced end projected toward the engine intake.

4. In a carbureter attachment, an agitator arranged in the pipe between the carbureter proper and the engine, embodying therein a helicoidal strand rotatable about an axis substantially coincident with the axis of said pipe.

5. In a carbureter attachment, an agitator arranged in the pipe between the carbureter proper and the engine, embodying therein a double helicoidal strand rotatable about an axis substantially coincident with the axis of said pipe, the greatest diameter of said agitator extending into close proximity to the said pipe.

6. In a carbureter attachment, an agitator arranged in the pipe between the carbureter proper and the engine, embodying therein a double helicoidal strand rotatable about an axis substantially coincident with the axis of said pipe, the greatest diameter of said agitator extending into close proximity to the said pipe and being centrally of said strand, said strand being reversely pitched from its central point.

7. In a carbureter attachment, a cylindrical casing adapted to be removably mounted within the pipe between the carbureter proper and the engine, bearings carried by the opposite ends of said casing, a shaft mounted in said bearings and a double helicoidal strand having its ends secured to said shaft, the greatest diameter of said helicoidal strand extending into close proximity to the 10 said pipe and being centrally of said strand,

said strand being reversely pitched from its central point.

In witness whereof I have hereunto affixed my signature, this 28th day of April, 1910, in the presence of two witnesses.

CHARLES SCHLAYER.
